UNITED STATES PATENT OFFICE.

WILBUR S. UPSON, OF MANSFIELD, OHIO.

WRENCH.

1,228,850.

Specification of Letters Patent. Patented June 5, 1917.

Application filed March 6, 1916. Serial No. 82,284.

To all whom it may concern:

Be it known that I, WILBUR S. UPSON, a citizen of the United States of America, residing at Mansfield, in the county of Richland and State of Ohio, have invented certain new and useful Improvements in Wrenches, of which the following is a specification.

This invention relates to wrenches, the jaws of which are adapted to be quickly and conveniently adjusted to engage various sizes of nuts, bolts, and the like and which are also operable to engage the nuts, bolts and the like through the medium of the usual screw feed.

The primary object of this invention is to provide a wrench with a stationary jaw and a coöperating movable jaw, the movable jaw of which is adapted to be freely, expeditely, efficiently and rapidly adjusted to engage different sizes of nuts, bolts and the like by instantly disengaging the actuating means from the movable jaw at the will of the operator, or if desired the actuating means can be operated to feed the movable jaw to engage various sizes of nuts, bolts and the like in the conventional manner.

The preferable specific means to accomplish the above described objects in brief comprise a worm nut pawl mounted upon a pivoted shaft and which is normally held in yielding engagement or mesh with a worm cog rack formed on the movable jaw.

These and other objects are attained by the mechanism illustrated in the accompanying drawing, in which:

Figure 1 is a side elevation partly in section of a wrench having the invention applied thereto, showing the worm nut pawl engaged or in mesh with the worm cog rack of the movable jaw.

Fig. 2 shows a section of the wrench on the line $\alpha\alpha$ of Fig. 1.

Fig. 3 is a side elevation of the wrench showing the worm nut pawl out of engagement with the worm cog rack of the movable jaw.

In the drawings reference numeral 1 represents the shank of the stationary jaw, 2 the stationary jaw and 3 the movable jaw. The movable jaw is provided with a shoe 4 having a worm cog rack 5 formed thereon. The shoe slidably engages the guideway 6 formed in the body portion 7 of the stationary jaw.

An aperture 8 preferably rectangular in form with rounded corners is formed in the enlarged body portion of the wrench. At a predetermined point in the body portion 63 of the wrench below the worm cog rack, an aperture 9 is formed which communicates with the aperture 8. One end of a shaft 10 which is smaller in diameter than the aperture 9 is pivotally journaled upon a pin 11 in the aperture 9 leaving its free end extending across the aperture 8 into a vertical slot 13.

A worm nut pawl 14 is mounted for rotation upon the shaft 10. The free end of 70 the shaft 10 is normally held in yielding contact with the upper wall of the slot 13, as shown in Fig. 1, by a coil spring 15 which is inserted in the aperture 16. The coil spring 15 is adjustably supported by the 75 screw 17.

In order to prevent the movable jaw from being opened too far or beyond a predetermined point, a key 18 is formed on the shoe 80 of the movable jaw and it depends into a slot 19 which provides a clearance for it and when the movable jaw is opened to the predetermined point it contacts with the shoulder 20 formed in the body portion of 85 the stationary jaw, thereby preventing further outward movement of the movable jaw.

The operation of the wrench, in brief, is as follows:

When it is desired to adjust the movable jaw rapidly to fit nuts, bolts or the like of 90 extreme differentiating sizes, the operator presses downward upon the worm nut pawl thereby counteracting the tension of the spring 15 and disengaging or forcing the worm nut pawl out of engagement or mesh 95 with the worm cog rack as shown in Fig. 3 which permits the ready, instant, free and expeditious adjustment of the movable jaw to fit the nut or bolt that it is desired to manipulate.

If the adjustment is slight, the operator if he prefers to do so can rotate the worm nut pawl to actuate the movable jaw for adjustment in the usual manner.

Attention is called to the fact that the 105 movable jaw can also be adjusted without pressing downward on the worm nut pawl by pressing against the movable jaw with the thumb toward the stationary jaw. Attention is called to the fact that the spring, 110 in exerting a pressure upon the spindle, performs a triple function, that is, it yieldingly

forces the worm cog-screw into mesh with the cog teeth; it forces and keeps the worm cog-screw and cog teeth constantly in frictional contact with each other, to thereby prevent the cog screw from turning through accidental contact to change the adjustment of the movable jaw; and it automatically takes up the wear of the parts.

I claim:

- 10 1. In a side jaw wrench, a handle made integral with a stationary jaw and an intermediate enlarged portion, said enlarged portion having a guideway formed therein in angular relation with respect to the handle and also having formed therein an intersecting angularly related aperture, a pin secured in the enlarged portion of the wrench, a spindle pivotally secured to said pin and adapted to extend across said intersecting aperture and to be moved to and from said guideway, a worm screw mounted upon said spindle, a movable jaw slidably mounted in said guideway and having a shoe thereon with a series of cog teeth, and yielding means adapted to normally maintain said worm screw in mesh with said cog teeth, but adapted to be withdrawn therefrom at the will of the operator, said last-mentioned means also performing the function of preventing the worm screw from turning under normal conditions because of the frictional yielding contact maintained between the
- 15

- 25
- 30

parts by said yielding means and automatically taking up the wear thereof.

2. In a side jaw wrench, a handle made integral with a stationary jaw and an enlarged portion, a guideway formed integral in the enlarged portion in angular relation with respect to the handle which intersects an aperture formed in said enlarged portion and which is angularly related thereto, a pin secured to the wrench, a spindle pivotally secured to said pin in such a manner as to extend across the aperture and which is adapted to be moved to and from said guideway, a worm screw mounted on said spindle, a jaw slidably mounted in said guideway carrying a shoe having a series of cog teeth formed thereon and extending into said intersecting aperture, and yielding means adapted to normally maintain said cog worm in mesh with the teeth of the jaw, but which is arranged to be disengaged at the will of the user, said last mentioned means also performing the function of preventing the worm screw from turning under normal conditions because of the frictional yielding contact maintained between the parts by said yielding means and automatically taking up the wear thereof.

In testimony whereof I affix my signature.

WILBUR S. UPSON.
